UNITED STATES PATENT OFFICE.

FITZ WILLIAM SARGENT, OF MAHWAH, NEW JERSEY, ASSIGNOR TO AMERICAN BRAKE SHOE & FOUNDRY COMPANY, OF JERSEY CITY, NEW JERSEY, A CORPORATION OF NEW JERSEY.

BRAKE-SHOE.

SPECIFICATION forming part of Letters Patent No. 749,103, dated January 5, 1904.

Application filed July 6, 1903. Serial No. 164,287. (No model.)

To all whom it may concern:

Be it known that I, FITZ WILLIAM SARGENT, a citizen of the United States, residing at Mahwah, in the State of New Jersey, have invented certain new and useful Improvements 5 in Brake-Shoes, of which the following is a specification.

My invention relates to the brake-shoes or wearing-blocks such as employed upon rail-way-car brakes, and particularly to that form of shoe which is cast and provided with a strengthening safety-back, generally made of sheet-steel.

The objects of my invention are to provide 15 a back for such brake-shoes which gives rigidity to strengthen the shoe, and at the same time has improved means for securing the back on the shoe by embedding it in the cast metal, to provide a back for a cast shoe which 20 is economical in material, easily put in place, securely fixed to the shoe at all points, and is itself of a form to give increased rigidity and strength against bending or fracture. These 25 objects and other advantages which will hereinafter appear I attain by means of the construction illustrated in preferred form in the accompanying drawings, wherein—

Figure 1 is a side elevation of my improved back for brake-shoes, the shoe being indicated in dotted lines. Fig. 2 is a plan view 30 of the back, with the shoe indicated in dotted lines. Figs. 3 and 4 are vertical cross-sections, taken, respectively, on the lines *x* and *y* of the other figures, through a cast 35 brake-shoe having my improved back inserted therein.

In order to allow of the greatest possible economy of metal in brake-shoes by providing 40 for complete wearing out of the same and at the same time to insure the shoe when worn thin against breaking into pieces and falling out of the head, it is customary to provide cast brake-shoes with a flat steel back, and various means have been devised for attaching 45 the back to the shoe in a secure and economical manner.

In my present improvement I make the 50 backing *a* of malleable metal in a generally flattened form, but slightly convex laterally throughout its length, so as to add stiffness to the back and at the same time provide for embedding the edge of the back in the metal

of the shoe, while the central part lies flush with the rear surface of the cast shoe. The back may conveniently have cut-out portions 55 *b* under the central lug and open portions *c* on the sides to economize metal. It is made of the curved or upwardly-convexed form laterally, as shown in Figs. 3 and 4, and is preferably embedded in the brake-shoe *d* in the 60 act of casting the latter, so that the convex part of the back will lie about flush with the surface of the back of the shoe and the outer edges of the back *a* will dip into the cast metal and be thoroughly embedded and anchored 65 therein along the entire length, as well as at the ends. This form attains all the stiffness that is possible without bringing the backing nearer to the wearing-face of the shoe, and at the same time provides for the 70 most secure anchorage of the backing in the shoe without any necessity for separate attaching devices or for cutting and stamping out portions of the back, which would very much weaken it.

The many advantages of the device will readily occur to those familiar with the use 75 of brake-shoes.

Having thus described my invention and illustrated its use, what I claim, and desire 80 to secure by Letters Patent, is the following:

1. A brake-shoe provided with a back longitudinally parallel with the face of the shoe and laterally convexed in section, the edges being embedded in the shoe in casting the 85 latter.

2. A cast brake-shoe having a steel back with downturned and embedded edges along its entire length.

3. A steel back for a brake-shoe being upwardly convexed along its entire length and lying flush with the back of the shoe with its edges embedded in the metal of the shoe.

4. A brake-shoe having a back composed of a steel plate convex crosswise and having 95 its edges embedded in the cast metal of the shoe, substantially as described.

In testimony whereof I have hereunder signed my name in the presence of the two subscribing witnesses.

FITZ WILLIAM SARGENT.

Witnesses:

RICHARD WANMAKER,
JOHN R. WANMAKER.
